ACCUMULATOR

Benjamin N. Ashton, Kingston, N. Y., assignor to Electrol Incorporated, Kingston, N. Y., a corporation of Delaware

Application May 1, 1953, Serial No. 352,550

3 Claims. (Cl. 138—31)

This invention relates to improvements in accumulators for hydraulic systems and it relates particularly to an improved and simplified type of piston-type accumulator suitable for use in aircraft hydraulic systems and in other high or low pressure hydraulic systems.

It has been proposed heretofore to provide piston-type accumulators which include a metallic cylinder having heads at its opposite ends and having a piston which is slidable lengthwise of the cylinder and divides it into a liquid-receiving chamber to be connected to the hydraulic system and a gas-receiving chamber to be filled with air or other gas under pressure. In many of these prior accumulators, difficulty is encountered in providing piston rings on the piston which provide a sufficiently good seal with the cylinder wall to prevent escape of gas and liquid past the piston and mixing thereof with resultant adverse effects on the hydraulic system.

In my Patent No. 2,440,065, dated April 20, 1948, and in my co-pending application Serial No. 337,553, filed February 18, 1953, I have disclosed several forms of sealing means which eliminate leakage of the gas and hydraulic liquid past the seals between the piston and the cylinder and mixing of them in the gas or liquid chambers of the accumulator. This desirable result is achieved by using resilient sealing rings or the like on the piston or in the cylinder and providing means for maintaining a pressure differential on opposite sides of the rings to thereby cause them to seat tightly against the cylinder and the piston to preclude leakage therebetween.

Even with my prior types of accumulators, the manufacture of the cylinder and the pistons and the provision of suitable cylinder heads and sealing means therefor produce engineering and production problems that render the accumulators more expensive and complex than is to be desired. Thus, in most of the prior accumulators, one or both ends of the cylinder have removable heads to permit access to the interior of the cylinder. Such removable heads require seals or packings therein to prevent escape of liquid and/or gas and, in some instances, a safety mechanism has been provided to prevent removal of the cylinder head while the pressure is still present in the hydraulic system or the accumulator.

I have discovered that the construction of the accumulator can be greatly simplified and that the accumulator cylinder can be reduced in complexity so that it can be manufactured more readily and at lower cost. Such a cylinder can be provided with seals of the resilient ring type for cooperation with the piston in the cylinder, these rings being so located with respect to the cylinder that they are inherently subjected to different pressures on their opposite sides to obtain the sealing action referred to above.

For a better understanding of the present invention reference may be had to the accompanying drawing in which the single figure is a view in longitudinal section through a typical accumulator embodying the present invention.

2

The accumulator 10 chosen for purposes of illustration includes a cylinder 11 in which is mounted an elongated hollow piston 12 consisting of a tubular skirt or sleeve 13 having piston heads 14 and 15 welded in its opposite ends. If desired, one or the other of the piston heads 14 and 15 may be omitted.

The tubular skirt 13 can be formed of polished but not necessarily precision honed tubing, such as stainless steel tubing or the like and it fits slidably within the cylinder 11 for free movement therealong. The piston 12 does not have to fit the cylinder 11 within close tolerances but their contacting surfaces should be smooth so that the piston moves freely in the cylinder without excessive radial play.

The cylinder 11 of the accumulator is of novel construction. It consists of two opposed hollow cup-like sections 16 and 17 which are of circular cross-section and generally cylindrical shape. The cylinder section 16 has a head 18 at its outer end which is integral with it and is provided with a passage 19 in which may be mounted an air check valve or the like through which air or other gas under pressure is introduced into the accumulator to the left of the piston 12. The cylinder section 16 has a thickened portion 20 at its right-hand end provided with external threads 21.

The cylinder section 17 is similar to the section 16 in that it also has a cylinder head 22 at its right-hand end provided with a passage and coupling 23 enabling it to be connected to the hydraulic system. The left-hand end of the cylinder section 17 also has a thickened portion 24 having a tubular extension 25 provided with internal threads 26 which are screwed on to the threads 21 of the section 16 to connect the cylinder sections in end-to-end relation, as shown in the drawing.

The thickened portions 20 and 24 of the cylinder sections have internal circumferential grooves 27, 28, respectively, therein. The grooves 27 and 28 receive resilient sealing members, such as, the O-ring seals 29 and 30 which bear against the bottoms of the grooves and the skirt 13 of the piston in all positions of the latter axially of the cylinder 11.

It will be apparent that when air or other gas under pressure is admitted into the cylinder to the left of the piston and the coupling 23 is connected to the hydraulic system, the piston will be displaced endwise in the accumulator cylinder as the pressures at opposite ends of it vary.

The ring seal 29 will be subjected to the pressure of the air on its left-hand side while the ring 30 will be subjected to the pressure of the liquid on its right-hand side. In order to provide maximum sealing effect with the rings 29 and 30 the pressures on opposite sides of each of the rings 29 and 30 are kept unequal, as explained in my Patent No. 2,440,065. In my new accumulator the threaded connection between the two cylinder sections 16 and 17 provides a suitable means for enabling the rings 29 and 30 to be subjected to unequal pressures. Thus, if the threads 21, 26 are not in gas-tight engagement, the space between the rings 29 and 30 will be at approximately atmospheric pressure while the pressures on the outer surfaces of the rings may be 1,000 lbs. per square inch or higher in an aircraft hydraulic system, for example. A porous packing 31 may be mounted within a groove 32 at the joint 33 between the two threaded sleeves to permit air to leave or enter the space between the rings 21, 26. If the threads are relatively tight-fitting or in substantially gas-tight relation, a radial bore 33 may be drilled through the sleeve 24 to communicate with the groove 32. In any event, the location of the sealing rings 29 and 30 makes it unnecessary to have the connection between the ends of the sleeves 16 and 17 leakproof. In fact, it is advantageous to have a

leaky joint between the sleeves 16 and 17 to increase the sealing efficiency of the rings 29 and 30.

It will be seen that the new accumulator is formed essentially of three pieces, not including the two sealing rings 29 and 30. The piston and accumulator sections do not have to be machined or honed to a precision fit because the resilient sealing rings 29 and 30 readily compensate for irregularities in the surface of the piston. The new accumulator does not need removable cylinder heads and the packings or seals which are required to maintain the heads in leak-tight relation to the cylinder. It may be fabricated from tubing or from simple castings with a minimum of finishing and precision operations.

It will be understood that the accumulator can be made in various sizes depending upon requirements and that if desired, a high pressure source, such as a small bag type accumulator, can be connected to the radial passage 33 to enable the accumulator member to be used in low pressure systems as suggested in my co-pending application Serial No. 337,553. Therefore, the form of the invention described herein should be considered as illustrative and not as limiting the scope of the following claims.

I claim:

1. An accumulator for hydraulic systems comprising a pair of hollow cylindrical members each having an open end and an integral cylinder head at its outer end, means connecting said members with their open ends in opposition to form a cylinder having the connecting means substantially at its midportion, an elongated piston-slidable axially in said cylinder and at all times extending into both of said cylindrical members, resilient seal-

25

5

ing members interposed between each cylindrical member and the piston, said sealing member being located on opposite sides of said connecting means and engaging said cylinder and said piston in all positions of the latter in said cylinder, and a passage from the interior of said cylinder between said sealing members to the outside of said cylinder.

2. An accumulator for hydraulic systems comprising a cylinder, said cylinder including a pair of hollow cup-shaped sections having complementally threaded open inner ends and integral cylinder heads at their outer ends, said cup-sections being screwed together to form a joint at about the middle of the cylinder and each having a groove therein adjacent to its open inner end, an elongated piston slidable in said cylinder, means to admit gas into and discharge it from said cylinder at said joint and resilient sealing means in each groove of said cup-sections on opposite sides of said joint and in sealing engagement with said piston in all positions of said piston in said cylinder.

3. The accumulator set forth in claim 2 in which the means to admit and discharge gas comprises a passage through the wall of said cylinder between said sealing means.
